UNITED STATES PATENT OFFICE.

ADOLPH MOSES, OF MOUNT VERNON, NEW YORK.

AUTOMATIC VENDING-MACHINE.

986,078.

Specification of Letters Patent. Patented Mar. 7, 1911.

Application filed April 9, 1910. Serial No. 654,365.

To all whom it may concern:

Be it known that I, ADOLPH Moses, a citizen of the United States, residing at Mount Vernon, in the county of Westchester and State of New York, have invented certain new and useful Improvements in Automatic Vending-Machines, of which the following is a full, clear, and exact specification.

My invention relates to improvements in automatic vending machines, wherein merchandise is delivered upon the insertion of a coin, and while it is applicable to a variety of constructions of such machines, it is shown as applied to a small, flat type of such device, suitable for use upon the back of theater chairs.

It has for its object to provide a new and improved form of lock for the delivery mechanism and in the means for releasing the same by a proper coin, and to this end my invention consists in the devices hereinafter described and fully shown in the accompanying drawings illustrating one form thereof, wherein—

Figure 1 is a sectional elevation of a structure embodying my invention on the line 1—1 of Fig. 2. Fig. 2 is a similar view on the line 2—2 of Fig. 1. Fig. 3 is a cross-section through the device on the line 3—3 of Fig. 4. Fig. 4 is a sectional elevation of part of the device, as in Fig. 1, with the slide extended; and Figs. 5, 6, and 7 are detail views in section, top and bottom views, respectively, of the slide.

The casing 1 is provided with a coin-chute 2, and with a vertical merchandise-holder 3, which may be of a piece of sheet metal bent to a shape conforming to the size of the packages of merchandise, and within which the packages 4 are held and fed by gravity, assisted, if desired, by a weight 4', to a package-receiving-recess 5, in a reciprocating-platform or slide 6. In this recess the packages are supported by a guiding-shelf 7, until they are carried out by the proper movement of the slide, when released by a coin, beyond the edge of the shelf, when they fall to a delivery-pocket accessible to the purchaser.

An inclined-plate 8, attached to a partition 9, or more than one such plate, if desired, may be employed to prevent the insertion of wires to rob the machine.

The slide 6 has longitudinal side-grooves

10 (Fig. 2), which receive the opposite sides of the shelf 7 and guide the slide on said shelf and permit its reciprocation. The parts of said shelf may be supported upon the casing 1, as shown, or in any suitable manner. The slide has a coin-slot at 11, which is beveled on one side, as shown (Fig. 2), for a purpose to be described, and which, when the slide is in position to be operated, is under inclined coin-chute 2. The shelf 7 is slotted at 12 to permit the passage of the coin. The slide 6 extends below the shelf 7, where, in connection with a vertically-reciprocating-dog 13, a slide-lock is formed. This dog is supported on the front of a stationary-block 14, fixed to the casing, by a headed screw 15, passing through an inclined-slot 16 in said dog and screwed into the block, and by a strap 17 which guides the dog and is attached to the block at one of its sides, thereby permitting the dog to tilt or oscillate about the screw 15 as a pivot, and also to move lengthwise thereof. A flat spring 18 is attached to the rear of partition 9, and its rear end passes under a shoulder 19 on the side of the dog and serves to press the dog upward.

The shelf 7 is formed with a downwardly-projecting short flange or lip 20, inclined to conform to the bevel of the coin-slot 11, and to a coin-receiving-recess 21, in the slide 6, below the coin-slot 11. This recess has a wall correspondingly beveled and extends sufficiently into the block 14 to permit the coin to pass under the shelf. The said flange 20 is situated as shown in Fig. 1, just forward of the coin-slot 11, when the slide is in starting position and opposite the dog 13, and a proper coin, for instance a copper cent 22, when inserted in the machine through chute 2, will pass through coin-slot 11 and into coin-recess 21, where it will rest against the beveled side and will, as it is propelled by the rear wall of the coin-recess in the slide, ride under the shelf and behind the flange 20 and be held in an inclined position while the coin is passing by and operating the dog. In this inclined position the coin, at substantially its most forward point, will encounter a lug 23, which may be beveled to facilitate its operation and will push the lug and dog sidewise, causing it to turn on screw 15 as a pivot. This will slightly raise a depressing shoulder 24 projecting from one

side of the dog, into the path of the coin, and the coin being held by the flange and restrained from upward movement by the shelf, will depress the dog 13. This depression, in the case of a proper coin, is sufficient to enable a retaining-shoulder 25 on the opposite side of the dog, to pass beneath the forward end of a detaining-rail 26. This rail has a downward bend to the rear of its forward end, and this operates still further to depress the dog so that it is brought down far enough to pass under an abutment 27, formed in the under side of slide 6. Detaining-rail 26 is secured on the inner wall 15 or side-flange 28, of the slide 6. This inner wall slides on a stationary-block 14, and the opposite inner wall 29 forms one side of the coin-recess and sideway.

Opposite the lower part of the coin-recess 20 21, and at one side of the block 14, is a magnet 30, the poles of which extend slightly above the bottom edge of the coin. This magnet serves to attract any magnetic disk that may be introduced and to retain it in 25 such position that it will not pass behind the flange 20 on the shelf. Thereby, as it is propelled forward by the slide, it will engage depressing-shoulder 24, and will swing same on pivot 15, until lug 23 engages the 30 side of such disk. This will not depress the dog sufficiently to allow the retaining-shoulder 25 to pass under detaining-rail 26, and consequently the dog will encounter abutment 27, on slide 6, and the slide will be 35 stopped before the package has reached the discharging position. Similarly, if a non-magnetic disk of less diameter than the proper coin should be inserted, it will not be held by the flange 20 and will therefore 40 not depress the dog sufficiently far to release the slide. A handle 31 is attached to the slide 6 and located outside the casing, which is slotted to permit the handle to reciprocate the slide.

45 The operation of my device should now be clear. The package-holder is loaded with packages and weighted by the weight 4'. A proper coin is dropped in through the coin-chute 2, and this being inclined, will 50 deliver the coin through the slot 11, to the coin-recess in the slide and underlying-block 14, so that the coin will lean against the beveled wall of the recess. The slide then is pushed forward by the handle 31, and 55 the rear wall of the coin-recess in the slide pushes the coin forward. It will naturally, on its entrance to the coin-recess, have rested on the beveled inner side, and will in this position pass under the shelf 7 and behind 60 the inclined, downwardly-projecting flange 20 thereon, and as it rides forward will tilt the upper part of dog 13 sidewise through lug 23, thereby causing depressing-shoulder 24 to rise. This being pressed down by the

coin, will sufficiently depress the dog, so that 65 retaining-shoulder 25 thereon will pass under detaining-rail 26, permitting the dog to clear shoulder 27 on the slide 6. The slide 6 will then continue its forward movement until the package, which in the meantime has dropped in the package-recess 5, has passed beyond the end of shelf 7 and has dropped to the delivery-pocket, whence the customer obtains it.

If, through any cause, the end of detaining-rail 26 should abut against retaining-shoulder 25, means are provided to operate the device consisting of an inclined slot 32, in a plate 33, supporting said rail, which receives a headed-pin 34, secured in side-wall 28, and causes the detaining-rail to recede, as it is pushed, and rise, whereby the retaining-shoulder passes under it. The detaining-rail will be returned by spring 41, secured to the slide. The locking shoulder 27 is situated to the rear of the coin so that if an improper coin or disk is inserted, while it will fail to release the locking dog, it will go forward far enough to be discharged and will not clog the machine.

Should a washer be inserted in the device instead of a proper coin, it may pass under the shelf and behind flange 20. The lug 23 will, however, enter the opening in the center and will not press the dog sidewise at 95 the proper time, which is when the greatest diameter of the washer is passing over the depressing shoulder, and will fail to operate the machine. Similarly a disk of magnetic metal, as iron, will be held by the magnet and will fail to depress the dog sufficiently, as will also a coin of proper metal but of too small diameter to be held in inclined position by the flange. So, also, a coin which is held by the flange will fail to 100 operate the dog unless of proper thickness and diameter. A cardboard disk will be inoperative, as it is not stiff enough to push aside the tilting-shoulder and ride over the depressing-shoulder so as sufficiently to depress same.

Numerous ways of indicating when the machine is empty may be employed. For instance, the weight 4', which will drop in the package-recess 5 when the packages are 115 exhausted, may have the word "Empty" on its side to be visible through a window in the casing; or a recess 40 may be constructed in the slide which will receive the bottom of weight 4' and hold the slide in the forward position by reason of the fact that said weight will enter the recess, but will not 120 pass entirely out of the package-holder.

I have illustrated but one embodiment of my invention. Numerous changes and modifications may be made in such embodiment without departing from the spirit of the same.

I claim:

1. In an automatic vending machine, a delivery slide, means for locking same comprising a locking abutment on the slide and a locking dog movable out of the path of said abutment, and means for holding a coin of proper diameter in position to move said locking dog out of the path of said abutment, and means independent of the coin for positively engaging the dog and holding the same out of said locking position during the operation of the machine.

2. In an automatic vending machine, a delivery slide having a coin-receiving slot, means for locking same comprising a locking abutment on the slide and a tilting locking dog movable out of the path of said abutment, coin-engaging and depressing means on said dog in the path of the coin, and adapted to be raised by the tilting of the dog, means for holding a coin of proper diameter in said slot in position to tilt said dog and to ride over said depressing means as the coin is advanced whereby the lock is released, and means for permitting a coin of less diameter to pass said dog ineffectively.

3. In an automatic vending machine, a delivery slide having a coin recess, means for locking same comprising a locking abutment on the slide, a tilting locking dog movable out of the path of said abutment by a tilted coin, means for holding a coin of proper diameter in tilted position in said coin-recess, and means independent of the coin for positively engaging the dog and holding the same out of said locking position during the operation of the machine.

4. In an automatic vending machine, a locking device and coin-actuated means for releasing same comprising a movable abutment, a locking dog normally in position to engage same, means permitting said dog to have a tilting movement and a movement out of the path of said abutment, a depressing shoulder on said dog in the path of the coin, a lug on said dog, the extremity of which is out of vertical alinement with the coin-engaging part of said shoulder.

5. In an automatic vending machine, a locking device and coin-actuated means for releasing same comprising a slide having a coin-receiving recess, a locking abutment thereon, a locking-tilting-dog movable relatively thereto, means for holding a coin in tilted position in said recess adjacent to said dog, a shoulder on said dog in the path of the coin, a tilting projection on said dog in position to engage the side of the coin, whereby said dog is moved out of locking position by the passage of a tilted coin, and means for holding the dog out of locking position during the operation of the machine.

6. In an automatic vending machine, a reciprocating slide having a coin recess therein, a lock for said slide comprising a locking projection therein, a locking dog in position normally to lock said slide and provided with a slot, a pin entering said slot and supported in the machine, whereby said dog may be tilted on said pin or moved longitudinally relative thereto, means for holding the dog normally in position to lock the slide, means for releasing the lock comprising a tilting projection on the dog, a depressing projection therein in the path of the coin, combined with means adjacent to said dog for holding a coin in position to engage said tilting and depressing projections.

7. In an automatic vending machine, a reciprocating slide having a coin recess therein, a lock for said slide comprising a locking projection therein, a locking dog in position normally to lock said slide and provided with a slot, a pin entering said slot and supported in the machine, whereby said dog may be tilted on said pin or moved longitudinally relative thereto, means for holding the dog normally in position to lock the slide, means for releasing the lock comprising a tilting projection on the dog, a depressing projection therein in the path of the coin, combined with means adjacent to said dog for holding a coin in position to engage said tilting and depressing projections, a retaining projection on said dog, and a detaining rail on the frame in position to hold said dog when depressed.

8. In an automatic vending machine, a reciprocating slide provided with a coin recess having a beveled side wall, a flange fixed to the machine forward of said coin recess in position to hold a coin against said beveled wall, a magnet in the frame adjacent said coin recess in position to hold magnetic disks from passing under said flange, and a lock for said slide adapted to be released by a coin held by said flange.

9. In an automatic vending machine, a reciprocating slide provided with a coin recess having a beveled side wall, a flange fixed to the machine forward of said coin recess in position to hold a coin against said beveled wall, a magnet in the frame adjacent said coin recess in position to hold magnetic disks from passing under said flange, and means for locking said slide comprising a locking abutment on the slide, a tilting locking-dog adapted to move lengthwise out of the path of said abutment, and means for imparting an unlocking movement to said dog comprising a tilting projection in position to engage the side of the coin at substantially a median line, and a depressing shoulder on the dog in the path of the coin.

10. In an automatic vending machine, a reciprocating slide provided with a coin re-

- cess having a beveled side wall, a flange fixed to the machine forward of said coin recess in position to hold a coin against said beveled wall, a magnet in the frame adjacent 65 to said coin recess in position to hold magnetic disks from passing under said flange, and means for locking said slide comprising a locking abutment on the slide, a tilting locking-dog adapted to move 70 lengthwise out of the path of said abutment, and means for imparting an unlocking movement to said dog comprising a tilting projection in position to engage the side of the coin at substantially a median line, a 75 depressing shoulder on the dog in the path of the coin, means for maintaining said dog normally in locking position, and means for holding the dog in unlocking position during the forward movement of the slide 80 when released by a coin.
11. In an automatic vending machine, coin-released locking means comprising a tilting dog, means for tilting said dog actuated by the coin, means for depressing the 85 dog also actuated by the coin, means for holding the dog normally in locking position, means for holding the dog in unlocked position comprising a retaining-shoulder on the dog and a coöperating rail on the frame.
12. In an automatic vending machine, coin-released locking means comprising a tilting dog, means for tilting said dog actuated by the coin, means for depressing the 90 dog also actuated by the coin, means for holding the dog normally in locking position, means for holding the dog in unlocked position comprising a retaining-shoulder on the dog and a coöperating rail on the frame movable lengthwise, combined with means 95 for causing the rail to rise as it is moved.
13. In an automatic vending machine, a locking device and coin-actuated means for releasing same, comprising a movable abutment, a locking dog normally in position to engage same, means permitting said dog to have a tilting movement and a movement 100 out of the path of said abutment, a depressing shoulder on said dog in the path of the coin, a lug on said dog, the extremity of which is out of vertical alignment with the coin-engaging part of said shoulder, and which is located in position to engage the side of the coin at substantially a median line.
14. In an automatic vending machine, a locking device and coin-actuated means for releasing same, comprising a slide having a coin-receiving recess, a locking abutment thereon, a locking tilting dog movable relatively thereto, means for holding a coin in tilted position in said recess adjacent to said dog, a magnet located in the frame adjacent to said coin-recess, a shoulder on said 115 dog in the path of the coin, a tilting projection on said dog in position to engage the side of the coin, whereby said dog is moved out of locking position by the passage of a tilted coin.
15. In an automatic vending machine, a reciprocating slide having a coin-recess 70 therein, a lock for said slide comprising a locking projection therein, a locking dog in position normally to lock said slide, and provided with a slot, a pin entering said slot and supported in the machine, whereby 75 said dog may be tilted on said pin or moved longitudinally relative thereto, means for holding the dog normally in position to lock the slide, means for releasing the lock comprising a tilting projection on the dog, a depressing projection therein, in the path of the coin, combined with means adjacent to said dog for holding a coin in position to engage said tilting and depressing projections, and a magnet in the frame opposite 80 said coin recess.
16. In an automatic vending machine, a movable platform having a coin recess, a locking device and coin-actuated means for releasing same, comprising means for holding a coin in tilted position on said platform, a tilting locking dog having tilting and depressing shoulders in the path of the coin, a detaining-rail on the slide and a retaining shoulder on the dog, the said parts 85 so combined and operating that a coin of proper diameter and thickness will, upon being held by said flange, tilt and depress said dog sufficiently to release the lock and cause the retaining shoulder to pass under 90 the retaining-rail.
17. In an automatic vending machine, a moving delivery slide having a coin recess, a locking device and coin-operated releasing means therefor, comprising a locking 105 abutment on said slide, a locking dog normally in the path of said slide, means actuated by the coin for removing said dog out of the path of said abutment, and means independent of the coin for positively engaging the dog and holding the same out of said locking position during the operation of the machine.
18. In an automatic vending machine, a movable delivery slide having a coin recess 110 adapted to propel a coin, a locking abutment on said slide to the rear of said recess, a locking dog forward of said coin recess adapted to be depressed by the coin, and means independent of the coin for holding 115 said dog depressed until the abutment on the slide has moved past the dog.
19. In an automatic vending machine, a reciprocating delivery slide provided with a coin slot, means for locking and releasing 120 said slide comprising a dog reciprocating in a plane, perpendicular to said slide, a stop on said dog adapted to coöperate with a stop

on said slide, a shoulder on said dog in operative position relative to a coin in said coin slot, and means independent of the coin for retaining said dog in released position, which are adapted to operate upon the movement of the slide past the coöperative point of said dog and coin.

In witness whereof I have hereunto set my hand in the presence of two subscribing witnesses.

ADOLPH MOSES.
